BEVERAGE DISPENSING STAND OR SIMILAR ARTICLE

James H. Parcher, Bala-Cynwyd, Pa., assignor to The Charles E. Hires Co., Philadelphia, Pa., a corporation of Delaware

Application February 18, 1952, Serial No. 18,563

Term of patent 7 years

(Cl. D2—3)

To all whom it may concern:

Be it known that I, James H. Parcher, a citizen of the United States, residing in Bala-Cynwyd, Montgomery County, State of Pennsylvania, have invented a new, original, and ornamental Design for a Beverage Dispensing Stand or Similar Article, of which the following is a specification, reference being had to the accompanying drawings, forming a part thereof, in which:

I claim:

The ornamental design for a beverage dispensing stand or similar article, as shown.

JAMES H. PARCHER.
